UNITED STATES PATENT OFFICE.

HENRY J. KOTSCHEVAR, OF MINNEAPOLIS, MINNESOTA.

GAS-GENERATING APPARATUS.

1,357,998.

Specification of Letters Patent.

Patented Nov. 9, 1920.

Application filed October 11, 1916. Serial No. 124,964.

To all whom it may concern:

Be it known that I, HENRY J. KOTSCHEVAR, a citizen of the United States, residing at Minneapolis, in the county of Hennepin 5 and State of Minnesota, have invented certain new and useful Improvements in Gas-Generating Apparatus; and I do hereby declare the following to be a full, clear, and exact description of the invention, such as 10 will enable others skilled in the art to which it appertains to make and use the same.

My invention has for its object to provide an apparatus for making, from hydrocarbon liquids, a permanent or fixed hydrocarbon 15 gas, or in some instances, for distilling hydrocarbon liquid of less specific gravity than the original hydrocarbon unit.

Particularly, the apparatus is designed for carrying out a process wherein the hydrocarbon liquid is cracked or broken up 20 by passing the same through molten metal, such as molten lead, for example. Experience has shown that when hydrocarbon oils are cracked or broken up by the gradual 25 application of heat, a part of the hydrocarbon will be separated in a sticky or pasty form much like tar and will adhere to the conduit or vessel through which it is passed, and accumulate to fill up and clog 30 the same. Experience has further shown that where the hydrocarbon oil is kept at a comparatively low temperature, and then caused to pass through molten metal, the carbon will separate into the form of a very 35 light, dry dust which will be carried off with the gas. The temperature at which the molten metal should be kept to produce this desired result will vary, depending in the first instance, on the kind of hydrocarbon 40 oil used, and in the second instance, on the product desired. The melting point of lead is approximately at 617 degrees F. For example, I have made a high grade permanent gas from kerosene by passing the kerosene 45 through molten lead at a temperature of approximately 900 to 1200 degrees F., although this temperature may vary somewhat, and have made such gas from gas oil by passing the same through molten lead 50 to a temperature varying from 1000 to 1400 degrees F.

The apparatus which I preferably employ is constructed substantially as shown in the accompanying drawings, wherein like characters 55 indicate like parts throughout the several views.

Referring to the drawings:

Figure 1 is a vertical section through the complete apparatus designed for making permanent gas from hydrocarbon oils; 60

Fig. 2 is an enlarged vertical section of the retort and immediately associated devices;

Fig. 3 is a plan view of one of the distributing so-called spreader rings used in 65 the retort;

Fig. 4 is a section on the line 4-4 of Fig. 3;

Fig. 5 is a fragmentary view in elevation showing one of the dust collecting 70 screens used in the dust collecting tank of Fig. 1; and

Fig. 6 is a view corresponding to Fig. 1, but illustrating a modification of the apparatus adapted for making the lighter hydrocarbon liquids from heavier hydrocarbon liquids. 75

First describing the apparatus illustrated in Figs. 1 to 5, inclusive, the numeral 7 indicates a furnace into which depends an air-tight metal retort 8, preferably of tubular form, having a flanged upper end and a head 9 detachably secured thereto. This retort 8 contains molten metal, such as lead, indicated at y, that is adapted to be kept in 80 molten condition by the heat from the furnace. Rigidly secured to and, as shown, formed integrally with the head 9 is a metal tube 10 that is closed at its lower end and is of much less diameter than the retort 8, 90 so as to afford the intervening annular space for the molten metal y. Spaced from the tube 10 is a smaller tube 11 and spaced from the said tube 11 is a still smaller tube 12. An air jacket is formed between the 95 tubes 10 and 11 and this air jacket is open at its upper end. A water jacket is formed between the tubes 11 and 12, and this water jacket is closed, both at its upper and lower extremities. The hot water runs out of the 100 upper end of this water jacket through a pipe 13, and the relatively cold water returns to the bottom thereof, through a pipe 14. Extended axially through the inner tube 12 but spaced from the walls thereof, is 105 a needle valve 15, the lower end of which is arranged to open and close a small port 16 in the extreme lower end of the said tube 12. The upper end of the tube 12 is provided with a stuffing box, through which 110 the reduced upper end of the needle valve 15 works with a gas-tight joint. Located

in the molten metal y and anchored to the retort 8 and outer tube 10 is a multiplicity of superimposed perforated so-called spreader rings 17, which serve to cause the 5 gas, in passing upward, to be spread and distributed throughout the molten metal. The numeral 18 indicates a multiplicity of metal balls of less specific gravity than the metal y and which float upon the upper surface thereof and prevent splashing of the molten metal by the gas which leaves the 10 upper portion thereon.

The hydrocarbon oil, as shown, is preferably contained in an air-tight tank 19 which 15 is kept under proper air pressure by air delivered to the upper portion of said tank through an air supply pipe 20. This oil is delivered from the bottom of the tank under the air pressure, through an oil delivery 20 pipe 21 that leads to the upper portion of the tube 12.

For automatically opening and closing the port 16, a thermally-actuated valve controller is provided in the valve 15. This 25 controller, as shown, comprises a brass tube 22 secured at its upper end to the head 9 of the retort and having a closed lower end. An iron or steel rod 23 rests at its lower end on the closed lower end of the tube 22 30 and extends upward therefrom and is connected to a small lever 24 that is intermediate pivoted to a bracket 25 as shown, on the upper end of the tube 12. At its outer end, this lever 24 has a weight 26, and at its 35 inner end, it is connected to the upper end of the valve 15, as shown, by a slot and pin connection 27. A light coiled spring 28 is interposed between the attached end of the lever 24 and a collar 29 on the said valve. 40 The weight 26 tends to keep the valve 15 upward and open the port 16, but when the metal y is cool, or cooled, the brass tube 22 will contract, and, acting on the said lever 24 will lift the weight 26 and cause the valve 45 15 to close the port 16. Under this closing action, the spring 28 will yield when the port 16 is closed and prevent buckling of the rod 23 or other parts, upon further contraction. Under increasing temperatures, 50 the tube 22 will expand much more rapidly than the rod 23 with a result that the weight 26 will remove the valve 15 upward and open the port 16 proportionate to the increasing temperature. Hence, there will be 55 permitted a flow of oil to the retort that is proportioned to or depending on the temperature of the molten material therein, and this is an action highly desired, because it will, of course, be understood that the higher 60 the temperature, the greater will be the amount of oil which may be "cracked" or broken up thereby, and furthermore, this increasing flow of oil will tend to keep down the increasing temperature of the molten 65 metal. Of course, within certain limits, the

regulation of the temperature will be made by control of the furnace, and this is also accomplished automatically by the use of the thermo-regulator already described. For example, in the smoke pipe 7^a of the 70 furnace there is a check damper 7^b, and this damper is connected to one end of a cable or cord 30 that is passed over a fixed guide sheave 31 and then brought down and attached to the extended end of the weighted 75 lever 24. Obviously, with this arrangement, under increasing temperatures, the check damper 7^b will be operated, thereby checking the fire. The rod 23 is preferably provided with a turn buckle 23^a by means of 80 which the valve 15 may be properly adjusted.

The gas formed in the retort is carried from the upper portion thereof through a pipe 32, which, in the preferred arrangement of the apparatus, leads to a closed carbon dust collector in the form of a casing 33. Within this casing 33, is a moistened carbon collecting screen 34 of burlap or other quite coarse woven fabric, preferably 90 hung in several layers over a perforated horizontal spraying pipe 35, which latter is supported at the lower end of a water supply of a small water pipe 36, the flow of water through which is regulated by a valve 37. 95 By the proper regulation of the water, this screen 34 is kept moist so it will catch and hold the carbon dust and other solid residue carried by the gas.

From the dust collector 33, the gas is 100 preferably carried to a washing tank 38, through a pipe 39 that terminates below the level of water y^1 contained in said tank. The washed gas passes out through a filter 40 in a pipe 41 by which it is carried to the 105 upper portion of an expandible gasometer 42-43. From the gasometer, the gas is carried through a service pipe 44 shown as equipped with a valve 45. The movable bell 43 of this gasometer is used as an automatic regulator for opening and closing a cut-off valve 46 in the oil supply pipe 21. This valve 46 may be of the usual "gate" type mounted for vertical movement, normally closed by a weight 47 applied to its 110 upwardly projecting stem. The weight 47 is connected to one end of a cable 48 passed over an overhead guide sheave 49 and extended down and attached to the top of the movable member 43 of the gasometer. 120 Whenever the supply of gas in the gasometer falls below a certain point, the weight of the bell 43, acting through the cable 48, will open the valve 46 and turn on the supply of oil, and when a certain amount of 125 gas has accumulated in the gasometer, the weight 47 will be permitted to close said valve 46 and cut off the supply of oil.

The water jacket, or combined water jacket and air pipe around the oil intake 130

5 tube keeps the oil at a temperature below its cracking point until it is actually brought into contact with the molten metal. This is very important, because it prevents the formation and collection of pasty or hard carbon residue on the interior of the oil intake tube. Otherwise stated, it delays the cracking 10 of oil and resulting formation of gas and carbon until the oil is subject to the hot molten metal. The term "molten metal" is herein used to indicate a metal that is in a liquid and hot condition. It would therefore include, for example, mercury heated to a temperature sufficient to crack the hydrocarbon liquid or other gas producing liquid.

20 The apparatus illustrated in Fig. 6, as indicated, is especially designed for making of the lighter or more volatile hydrocarbon liquids from the heavier hydrocarbon oils. It may be the same apparatus illustrated in Figs. 1 to 5, inclusive, with the carbon collecting receptacle 33 and washing tank 38 omitted and with condensers A and B, respectively, substituted for the said devices 33 and 38. The condenser A involves a manifold condensing pipe 50 connected to the pipe 32 and at its lower portion, having a depending discharge port 51 that opens into 25 a condensate tank 52. The manifold 50 delivers to the upper portion of a manifold 53 of the second condenser B. The lower portion of this manifold 53 is contained in a water tank 54 which has circulating connections 55 for supplying cold water to increase the condensation. The lower extremity of the manifold 53 delivers into a second condensate tank 56, the upper portion of which may be connected to the pipe 41 that 30 leads to the gasometer 42-43. With this apparatus illustrated in Fig. 6, the gas generated in the retort will be condensed in passing through the manifold or cooling pipes 50 and 53 and precipitates of different specific gravity will be accumulated in the tanks 52 and 56. For example, a distillate of about the specific gravity of kerosene may be precipitated in the tank 52 and a distillate of about the specific gravity of 35 gasoline may be precipitated in the tank 56. A gas which passes from the tank 56 will be delivered into the gasometer 42-43 and the accumulation thereof caused to automatically control the valve 47.

40 The pipe 50 is preferably provided with an automatic pressure regulating valve 50^a of well known construction such as commercially sold on the market designed to give the necessary pressure in the retort required 45 under varying temperatures of the molten

metal to produce the kind of product desired.

5 In practice, the condensers A and B, instead of being substituted for the devices 33 and 38, may be connected to the retort independently thereof and used only when desired.

65 For the production of various different gases, or for the distillation of hydrocarbons of different specific gravity, or both, different molten metals may be employed in the retort. Lead will probably be employed in most instances. However, aluminum, which has a fusing point of a little less than 1200 degrees F., may be used for 70 the production of a gas requiring that high temperature. For all gases, the carbon from the "cracked" oil will have a dry powder form and will not stick or adhere to the walls of the retort or of the conduits, but 75 will be mostly carried by the gas until precipitated therefrom, in the proper receptacle. Even if there should in time be an accumulation of this dry carbon dust within the retort it will not form a scale and 80 may be easily removed by opening the retort from time to time. The elimination of the carbon deposits from the walls of the retort maintains a maximum thermal efficiency and prolongs the life of the retort. 85

90 What I claim is:

1. An apparatus for producing gas from gas producing liquids, comprising a closed heated retort containing molten metal, a cool medium jacketed oil delivery tube leading 95 down through said molten metal to a point near the bottom of said retort, a valve for controlling the discharge of oil from said oil delivery tube into said molten metal, and a thermally-actuated controller for said 100 valve, whereby the oil will be variably supplied under varying temperature of the said molten metal.

2. An apparatus for producing gas from gas producing liquids, comprising a closed heated retort containing molten metal, an oil delivery tube leading downward through said molten metal to a point near the bottom of said retort, a water jacket surrounding said tube, an air jacket surrounding said water jacket, the said oil delivery tube having a discharge port at its extreme lower end, and a valve for opening and closing said port. 110

115 In testimony whereof I affix my signature in presence of two witnesses.
